MAN MFG. CO., OF NORRISTOWN, PENNSYLVANIA, A CORPORATION OF PENNSYL-
VANIA.

TAKE-UP MECHANISM FOR KNITTING-MACHINES.

1,203,092.

Specification of Letters Patent.

Patented Oct. 31, 1916.

Application filed January 4, 1916. Serial No. 70,209.

To all whom it may concern:

Be it known that I, GEORGE LAWSON BAL-
LARD, a subject of the King of Great Britain,
residing at Norristown, Pennsylvania, have
5 invented certain new and useful Improve-
ments in Take-Up Mechanism for Knitting-
Machines, of which the following is a speci-
fication.

The invention relates to take up mecha-
10 nism for knitting machines.

I have shown the invention for conven-
ience of illustration in connection with the
form of take up mechanism disclosed in Let-
ters Patent of the United States No. 600,568,
15 granted March 15th, 1898, though it will be
understood that the invention is not limited
to a mechanism of the particular character
shown.

One object of the invention is to provide
20 an automatic control for the take up mecha-
nism to maintain the relation of said mech-
anism to the fabric, which is predetermined
upon for the best effect.

The invention is shown in the accompany-
25 ing drawings, in which,

Figure 1 is a plan view of a take up mech-
anism, embodying the invention. Fig. 2 is
a side view of the mechanism shown in Fig.
1, and Fig. 3 is a detail view looking from
30 the left of Fig. 1 with parts in section and
parts in elevation and with parts omitted.

In these drawings, A, A are the usual take
up rolls journaled in a take up frame B
which is pivotally mounted in connection
35 with a fixed frame C, forming a part of the
fixed frame of the machine. The rollers A,
A are geared together by gears D, D and
the shaft of one of the take up rolls carries
a worm wheel E engaging a worm F on a
40 vertical shaft G mounted in bearings g of
the pivoted frame B. The shaft G carries a
beveled gear H, meshing with a beveled
gear I on a horizontal shaft J mounted in
bearings as J' in a bracket forming part of
45 the frame B. Power is transmitted to the
shaft J from a moving part of the machine,
such for instance as the pulley 3, which is
mounted on a shaft 3', which is the drive
shaft of the machine and which is mounted
50 in fixed bearings on the frame. Motion is
transmitted from this pulley through a con-
nection which will permit the frame B to
have vertical movement, and in the particu-
lar construction shown, this consists of a
55 belt or rope 2 of endless form, which passes

around a pulley 5, which is fixed on the
shaft J above mentioned, this pulley 5,
therefore, in effect being mounted on the
pivoted frame B and partaking of any ver-
tical movement or tendency to vertical move-
60 ment, that the pivoted take up frame B may
have. The pulley 5 being rotated by the
endless belt 2, the motion will be trans-
mitted through the shafts J and G and
worm F and worm wheel E to one of the 65
take up rolls A and this, through the gear-
ing D, D will drive the other take up roll to
feed the fabric downwardly as it comes from
the needles.

As the pivoted frame B, by its weight and 70
the weight of the parts carried thereby, ap-
plies the desired tension to the fabric, it is
desirable to maintain said frame in the posi-
tion predetermined upon for the best effect.
The preferred normal position of the frame 75
is horizontal and when in this position the
full effect of the weight on the fabric gripped
between the take up rolls, is being exercised.
However, this horizontal position of the
frame, as being the normal one, is subject to 80
change for the reason that the rope or belt
may stretch under considerable use and the
normal position of the frame would there-
fore be lower than the horizontal. Further-
more, all belts or ropes are not of precisely 85
the same length to start with but whatever
the length of the rope may be a normal po-
sition of the frame to weigh or hang on the
fabric is established by the attendant and
one object of the invention is to maintain 90
the frame in this position as near as possible
whether it be horizontal or above or below
the horizontal. When the frame is in nor-
mal position hanging or weighing on the
fabric the relation of the length of belt to 95
this position is such that said belt will slip
on the pulley but upon slight downward
movement of the frame the rope or belt will
grip the pulley to rotate the roll or rolls and
being rotated faster than the fabric is knit, 100
the said rolls will creep up or climb on the
fabric to normal position and will be ar-
rested by the pulley 5 pressing upon the
brake device. This brake device may as-
sume various forms but in the particular 105
construction shown, it is in the form of a
brake shoe 4 consisting of a fiber disk to
engage the periphery of the pulley. As
above stated, the pulley 5 is fixed to the
shaft J and when its motion is retarded or 110

stopped the take up motion of the rolls A A will be decreased or stopped.

The brake device is held rigidly in fixed position by a bar or rod 6, which is held by 5 a set screw 7 in bearings or ears 8 of the fixed frame C. The rod furnishes the journal upon which the frame B turns and the brake shoe is held by an extension of this rod. This rod can be adjusted by loosening 10 the set screw 7 and turning the rod 6 in its bearings and the position of the brake shoe may be changed to accord with the normal position at which the take up frame is to be maintained.

15 Without my device to stop the rotation of the driven pulley, experience has demonstrated that, when the takeup falls low enough to tighten the belt and start the driven pulley, the grip of the belt in the 20 grooved pulley will be sufficient to keep it going, long after the frame has reached its normal position. Less grip of the rope is required to keep the pulley going once it is started, than is required to overcome its 25 inertia on starting it.

The described usual form of takeup rolls rolls are always rotated faster than the fabric is knitted. It follows therefore that the takeup will climb up on the fabric. The 30 grip of the rope will not be released until the takeup is too high to have the same weight on the fabric as when it is in normal position. When the takeup falls low enough to tighten the belt, and start the 35 pulley, the weight on the fabric is materially lessened, as the weight on the takeup is largely absorbed by the belt, that is it is not all on the fabric. As soon as the pulley revolves, there is immediately more 40 weight on the fabric, as less weight is required to maintain a grip on the rope to rotate the pulley than to start it. Inertia, and momentum of the pulley contribute to this effect.

45 The form of takeup used for illustration has two takeup gripping rolls. My invention is not limited to two gripping rolls. It may be employed in connection with takeups having only one roll, over which 50 the fabric is drawn, it being held against the roll by suitable guide bars to maintain a frictional contact. My invention provides effective means to maintain practically uniform weight, or pulling down effect on 55 the fabric and particularly on the types of machines where the takeup is belt, or rope driven. The maintenance of constant weight is due to a means for stopping the rotation of the rolls and forcing the driven 60 belt to slip intermittently, and without material effect on the normal, or predetermined position of the frame and takeup devices; also my invention maintains a practically uniform tension of the belt, which would 65 otherwise be alternately tight and slack and

neutralize the weight intended for the fabric.

While I have described the frame and takeup rolls as having a rising and falling movement, I have used this description more 70 especially for convenience. Theoretically however, no marked up and down movement of the takeup frame takes place when perfect working condition exists. The pulley 5 may be in contact with the brake shoe 4 75 constantly. This contact is light at times permitting the pulley to rotate when the frame tends to fall below normal position, whereas when the takeup rolls tend to creep upon the fabric and carry the take up 80 frame up with them, the pressure of the pulley 5 against the brake shoe is increased sufficiently to retard or stop the rotation of the pulley and the takeup rolls.

It will be understood that while I have 85 described a rope or belt drive for the pulley 5, I do not limit myself in this respect, but would point out that some form of drive is necessary that will permit a tendency of the takeup frame to rise and fall and hang 90 or weigh on the fabric.

I do not wish to exclude from the scope of my invention an organization in which actual movement of the takeup frame takes place as under some conditions, this will 95 occur, but excessive creeping up of the takeup rolls on the fabric will be prevented in such cases by the pulley 5 coming in contact with the brake shoe. Where in the appended claims I refer to the takeup 100 frame with the roll or rolls having an up and down movement in relation to the fabric and brake, it will be understood that I employ these words in a generic sense to include an actual movement or a tendency to 105 have such movements and I do not wish to be understood as limiting my invention in this respect.

What I claim is:—

1. In combination in a take-up for knitting machines, gravity take-up means weighing on the fabric and tending to climb thereon, a friction drive for said take-up means and a brake means for applying restraining pressure to said drive when the take-up 115 means tends to climb on the fabric, substantially as described.

2. In combination in a take up mechanism for knitting machines, a pivoted frame extending substantially in a horizontal plane 120 from its pivot when in normal position, a take up roll or rolls carried by said pivoted frame, a pulley mounted on said pivoted frame, connections intermediate the pulley and the roll or rolls for driving the same, a 125 belt or rope for driving the said pulley, said belt or rope extending upwardly from the pulley, so that its frictional driving contact with said pulley will be modified by the rise and fall of the pivoted frame and means 130

- rendered effective by the rise of the pivoted frame to retard the rotation of the pulley when the frictional pressure of the belt is reduced, substantially as described.
- 5 3. Take up mechanism for knitting machines, comprising a pair of take up rolls, a movable support for said rolls, means for driving the rolls, and means for applying restraining pressure to said driving means
- 10 when the said support and rolls move upwardly from normal position, substantially as described.
- 4. Take up mechanism for knitting machines, comprising a pair of take up rolls, a movable support therefor, said rolls tending to creep up on the fabric if the taking up action is too fast, driving means for the take up rolls carried by said support, and a brake for applying a restraining pressure
- 15 to said driving means when said rolls and support move upwardly in respect to the fabric, substantially as described.
- 5. Take up mechanism for knitting machines, comprising a pair of take up rolls, a movable support therefor, said rolls tending to creep up on the fabric under certain conditions, driving means for the take up rolls carried by said movable support, and means for applying braking pressure to the
- 20 driving means rendered effective by the upward movement of said rolls and support, substantially as described.
- 6. Take up mechanism for knitting machines, comprising a pair of take up rolls, a movable support therefor, said rolls tending to creep up on the fabric under certain conditions, a drive pulley mounted on the said movable take up frame, driving connections between said pulley and the take up rolls,
- 25 a belt for driving the pulley, and means for applying restraint to the driving connections when the frame rises.
- 7. Take up mechanism for knitting machines comprising a pair of take up rolls, a pivoted support therefor, said rolls tending to creep up on the fabric under certain conditions, a drive pulley mounted on the said movable take up frame, driving connections between said pulley and the take up rolls,
- 30 a belt for driving the pulley, and means for applying restraint to the driving connections when the frame rises.
- 50 8. In combination in a take up for knit-
- ting machines, take up rolls, a movable support therefor, driving means for the rolls mounted on said movable support, and a fixed brake normally out of action but on which the driving means presses when the take up rolls and support rise in relation to the fabric, to thereby retard or stop the take up rolls, substantially as described.
- 9. In combination in take up mechanism for knitting machines, take up rolls, a pivoted frame in which said rolls are mounted, driving means for the take up rolls mounted on the pivoted frame, and a brake which is set for pressing upon and retarding or stopping the said driving means when the pivoted frame rises, substantially as described.
- 10. In combination in take up mechanism for knitting machines, take up rolls, a pivoted frame in which said rolls are mounted, driving means for the take up rolls mounted on the pivoted frame, and a brake which is set for pressing upon and retarding or stopping the said driving means when the pivoted frame rises, said brake being rendered effective as a result of the rise of the frame and take up rolls.
- 11. In combination in take up mechanism for knitting machines, take up rolls, a pivoted frame in which said rolls are mounted, a driving pulley mounted on the pivoted frame, connections from said pulley to the take up rolls for driving the same, a belt drive for the pulley, and a brake shoe in fixed position against which the pulley presses when it rises with the frame and take up rolls, substantially as described.
- 12. In combination, take up rolls for knitting machines, a pivoted frame, a pulley mounted on the frame, driving connections between the pulley and take up rolls, a belt for driving the pulley, a shoe arranged over the pulley and a bracket supporting said shoe in fixed relation, said bracket forming the journal for the pivoted frame, substantially as described.

In testimony whereof, I affix my signature in presence of two witnesses.

GEORGE LAWSON BALLARD.
